UNITED STATES PATENT OFFICE.

HERBERT OLIN BRIGHAM, OF PROVIDENCE, RHODE ISLAND.

FILING DRAWER AND COMPARTMENT.

No. 860,898.

Specification of Letters Patent.

Patented July 23, 1907.

Application filed January 4, 1907. Serial No. 350,774.

To all whom it may concern:

Be it known that HERBERT OLIN BRIGHAM, a citizen of the United States, residing at Providence, in the county of Providence and State of Rhode Island, has 5 invented certain new and useful Improvements in Filing Drawers and Compartments, of which the following is a specification.

My invention relates to all kinds of filing-drawers, compartments, or receptacles, in which documents, 10 pamphlets, and like articles are placed for proper keeping and ready reference.

It is my intention to provide a means whereby the said articles may be readily removed from said drawers, receptacles, etc., after they have been compressed by 15 a compressor-board, by supplying an easement at the front of the same in the form of a combined handle which, by a single turn thereof a movable board situated at the inside of the front of drawer, will be carried a short distance toward said front, thereby reducing 20 the pressure upon the contents of drawer, allowing any or all the contents to be readily removed, also with the same movement of handle, unlock the drawer at the top or sides, or bottom, as the case may be.

It has been the custom in the past to supply all of the 25 pressure with a compressor-board at the back of the contents of the drawer, as in the ordinary vertical letter and document files. To remove any of the contents of drawer, the compressor board is released more or less after the drawer has been withdrawn, and if it should 30 be full, it would have to be entirely withdrawn for the operation of the compressor.

The new feature shown herein permits the contents 35 of the drawer to be released of sufficient pressure for the removal thereof with ease, when the handle is turned, prior to the pulling out of the drawer. I accomplish this by placing a cam-action (plates) between the front 40 of the drawer and a board upon the inside thereof, a spindle at the center of one plate entering the center of the other plate for guiding purposes, a cam upon the portion of handle passing through the front of drawer which acts upon one or more bolts used for locking purposes, and a suitable cross-bar handle at the outside front of drawer for manipulation.

I attain these objects by the special construction 45 illustrated in the accompanying drawings, in which

Figure 1, is a sectional side view of a filing-drawer showing the contents compressed by the expansion of the cam action on cam-plate, and the locking-bolt at the top of the drawer. Fig. 2, is a sectional view of 50 the handle to better illustrate the details of construction.

Similar letters refer to similar parts throughout the several views.

A is the front of drawer; B is the bottom of drawer; C is the compressor-board; D is the board which receives the action of the cam-handle; E represents pamphlets filed; F is a cam-plate; G is the cam end of handle; H is a centrally located cam acting on the locking-bolt; I is the handle in front of drawer; J is a guiding spindle in center of cam-plate; K is the locking-bolt; L is the escutcheon plate; M socket to receive J.

In operation, the drawer is locked and the contents are held in compressed form when the various parts are in position shown in Fig. 1: To pull out the drawer, handle I is turned which operation turns cam-end G of 65 handle, which permits board D to move a short distance toward front of drawer, thereby easing the pressure on the contents E, permitting the withdrawal of any or all of the material filed. The turning of the handle I also turns the cam H which permits locking-bolt K to fall thereby unlocking the drawer. After reference and return of contents to the drawer, it is pushed back in its case and handle I turned which forces back board D and compresses the contents, also forces locking-bolt K upward causing it to enter the casing above 70 thereby locking the drawer.

Having clearly described my invention so that those skilled in the art will thoroughly understand the same, what I claim as my invention and desire to secure by Letters-Patent of the United States is:—

1. In a drawer or receptacle for filing books, documents or pamphlets, a means for permitting the contents thereof to expand, consisting of a cam at the inner end of the handle of the drawer, and a cam-plate upon the engaging surface of compressor board or plate C, all as and for the purpose specified.

2. In a drawer or receptacle for filing books, documents or pamphlets, and the like, a handle for pulling out the same, having a suitable form at end I for turning, a cam-end G for action upon cam-plate F, and a side-cam H for action upon locking-bolt K, in combination with the board D carrying cam-plate F, all as shown and for purpose specified.

3. In a filing device, in combination with end thereof, a board or plate D carrying cam-plate F, a locking-bolt K 95 in the drawer-front, and a handle situated in line with cam-plate F and locking-bolt K, and having cams for action thereupon.

4. As a new article of manufacture, a pressure-release and locking device in combination with a handle, for filing 100 drawers or other receptacle, all as shown and for purpose specified.

In testimony whereof I affix my signature in the presence of two witnesses.

HERBERT OLIN BRIGHAM.
